M. BUCHHOLZ

ELECTRIC PROTECTIVE SYSTEM

Filed April 16, 1925

Inventor:

Max Buchholz

by Atty.

UNITED STATES PATENT OFFICE.

MAX BUCHHOLZ, OF CASSEL, GERMANY.

ELECTRIC PROTECTIVE SYSTEM.

Application filed April 16, 1925, Serial No. 23,679, and in Germany October 6, 1924.

My invention has reference to a method and means for protecting electric apparatus operating in an insulating liquid, such as oil transformers, oil switches, grounding throttling coils, resistances and the like, and it is one of the important objects of my invention to provide a device of very simple construction and great reliability, and adapted to operate before extensive injuries

10 to the apparatus to be protected can occur by sparking, overloading or other disturbances.

My invention is particularly based on the fact that in the case of disturbances in the operation of the apparatus to be protected 15 or in the case of sparking or other irregularities of operation, or whenever such irregularities are imminent, as well as in the case of any ebullition or fermentation processes in the oil, serving as an insulating 20 liquid, bubbles of gases of decomposition are formed which can operate a protective means, for instance an electric contact, either a working or a closed contact, which is adapted to switch out of circuit the apparatus 25 to be protected, or which will operate an alarm or annunciator device indicating the disturbance, or which is adapted to effect both kinds of operations. The gases formed by decomposition may influence the contacting 30 means in different ways.

According to the present invention I utilize the property of the gases or vapors generated from the insulating liquid and more especially insulating oil by decomposition 35 or from other causes to be absorbed by certain substances, such as for instance platinum black. I can also utilize the property of these gases to chemically combine with certain substances which need not be solids.

40 In consequence of such absorption or combination the weight of the substances in question is increased correspondingly. This increase in weight can now be utilized for operating a mechanical or electric contact device arranged for operating a protective 45 switch, alarm, annunciator device or the like adapted to cut out or to announce an unnormal condition of working of the transformer or other apparatus to be protected.

50 In the drawings affixed to this specification and forming part thereof an arrangement embodying my invention is illustrated diagrammatically by way of example.

In the drawings, *a* is a transformer vessel 55 or container and *b* is the insulating oil or other liquid filling same and surrounding the

apparatus (not visible) to be protected, this insulating liquid developing gases or vapors containing for instance hydrogen, methane or the like whenever the normal operation of the apparatus surrounded by it is disturbed. *c* is the cover closing the container *a* and *o* is a nozzle-like tubular extension mounted on said cover and communicating with the interior of the container. *p* is a double-armed contact lever carrying at one end a contact piece *k* capable of making and breaking contact with the other terminal of a protective circuit *m* comprising an oil switch, fuse, alarm or other annunciator device. To the other end of the lever *p* which extends above the nozzle *o* there is attached a mass *s* consisting of, covered with or containing platinum black or some other substance capable of absorbing, occluding or chemically combining with one or several of the gases developed from the insulating liquid.

Obviously, when such gases are developed and escape through the nozzle *o*, they will be 80 absorbed by the mass, and the resulting increase in weight will cause the mass *s* to descend, whereby the contact piece *k* is made to close the circuit *m* and to operate the safety device inserted in it.

Instead of arranging the absorbing mass at one end of a lever, I may as well also arrange it within the container *a* above the liquid level, the connection between it and the contact making device being established 90 for instance by some suspension means.

The circuit to be controlled by the contacts referred to may excite either directly or by the medium of an intermediate relay the releasing coil of an oil switch which 95 interrupts the endangered circuit. In the case of apparatus the circuit of which does not include an oil switch, as frequently occurs, for instance in the cases of transformers mounted in the field at wide distances apart, other provisions should be 100 made for the purposes of this invention.

Beside the form of construction herein shown and described, the invention is susceptible of a variety of other modifications 105 and forms of application of the principle of my invention all of which operate substantially in a similar manner. The means of connecting the contacting device with the releasing circuit and the switching means 110 are open to changes and alterations without any material importance for the operation

2
of the apparatus according to my invention which in its broad aspects comprises the operation of safety devices for electric apparatus or the like, adapted for operation by vapors, fumes, gases or similar emanations liberated and expelled from the insulating medium, and means adapted to be operatively influenced by such emanations, and connected to fuses or equivalent safety means, the instrumentalities shown and described in this specification as embodiments of these principles being susceptible of modifications without deviating from the spirit of my invention as set forth in the claims.

15 In the claims the term "gases" is meant to comprise also vapors and fumes.

I claim:—

1. Protective system for liquid-insulated electric apparatus, comprising a supply of insulating liquid, which, when decomposed, develops gases containing an absorbable gas, a substance disposed near said liquid which is capable of absorbing gases developed from said liquid and protective means con-

nected with and rendered operative by an increase in weight of said substance.

2. Protective system for liquid-insulated electric apparatus, comprising a supply of insulating liquid, which, when decomposed, develops gases containing an absorbable gas, a protective circuit, a balanced contact lever above said liquid and a mass connected with the free arm of said lever capable of absorbing gases developed from said liquid resulting in shifting said lever and affecting the operative condition of said circuit.

3. The method of controlling abnormal working conditions of liquid insulated apparatus which comprises subjecting a substance adapted to absorb gases to contact with gases developed in the insulating liquid in consequence of abnormal conditions and causing the resultant increase in the weight of such substance to vary the operative condition of protective means.

In testimony whereof I affix my signature.

MAX BUCHHOLZ.
